Attorneys.

United States Patent Office.

B. RAVEN, OF PLEASANTVILLE, PENNSYLVANIA.

Design No. 3,572, dated July 6, 1869.

DESIGN FOR A TABLE-KNIFE.

The Schedule referred to in these Letters Patent and making part of the same.

To all whom it may concern:

Be it known that I, B. RAVEN, of Pleasantville, in the county of Venango, and State of Pennsylvania, have invented a new and improved Design for Table-Knife; and I do hereby declare that the following is a full, clear, and exact description thereof, which will enable others skilled in the art to make and use the same, reference being had to the accompanying drawing, forming part of this specification.

This invention relates to a new and ornamental design for the form of table or other knives.

The drawing represents a view of a table-knife constructed in the form of my improved design.

Between the bolster A and heel B of the blade, I introduce a curved neck, C, preferably of oval form on

the top, B, where the fore-finger of the hand will naturally press, when cutting.

The curvature of the neck continues to some extent beyond the junction of the latter with the heel of the blade, giving the bit of the blade a forward "set," ornamental in form and appearance, and useful in cutting.

Having thus described my invention,

What I claim as new, and desire to secure by Letters Patent, is—

The design for table and other knives, herein shown and set forth.
